UNITED STATES PATENT OFFICE.

SEYMOUR C. PALMER, OF SOUTH NORWALK, CONNECTICUT, ASSIGNOR, BY DIRECT AND MESNE ASSIGNMENTS, TO ELLEN M. PALMER AND ALDEN SOLMANS, BOTH OF SAME PLACE.

HAT-FORMING MACHINE.

SPECIFICATION forming part of Letters Patent No. 415,217, dated November 19, 1889.

Application filed May 23, 1889. Serial No. 311,833. (No model.)

To all whom it may concern:

Be it known that I, SEYMOUR C. PALMER, a citizen of the United States, residing at South Norwalk, in the county of Fairfield and State 5 of Connecticut, have invented certain new and useful Improvements in Hat-Forming Machines; and I do hereby declare the following to be a full, clear, and exact description of the invention, such as will enable others skilled 10 in the art to which it appertains to make and use the same.

My invention relates to hat-forming machines of the general construction and operation shown and described in my Letters Patent 15 of the United States, No. 399,551, issued March 12, 1889. The operation of dipping the hats had always been performed by hand until I invented the machine shown and described in said patent, and I am therefore the 20 pioneer in the art of automatically dipping hats. This being the case, and realizing that my invention is of great value to the hat-manufacturers, I desire to protect myself as against piracy and possible evasion of my 25 patented invention; and the object of my present invention is to protect myself in the use of automatically-controlled mechanism for dipping a hat, wherein the connection between the cone-supporting platform and the 30 motive power is not a rigid rod, but is a rope or any suitable cable.

My present invention consists in suspending the cone-supporting platform from a rope or cable, the latter being run over a pulley or 35 drum and connected with any suitable means for raising or lowering said rope or cable.

As various mechanisms may be utilized to draw up or pay out the rope, and as I do not desire to be circumscribed by the use of any 40 particular mechanism for this purpose, I have made my drawings extensive and elaborate, so that the fundamental merits of my invention will be readily understood.

In the drawings, Figure 1 is an elevation 45 illustrating my invention, wherein the rope is connected to a revolvable crank and to the bail of the cone-supporting platform; Figs. 2 and 3, similar views showing the rope running over an ordinary pulley tight on a revolvable

shaft. Fig. 4 shows the rope adapted to be 50 operated by hydraulic means. Figs. 5 and 7 show the rope connected as shown at Fig. 1, but controlled and operated by foot-power; and Fig. 6, a section at the line *x x* of Fig. 1.

Similar letters denote like parts in the several figures of the drawings.

A is the dipping-tub, and B the cone-supporting platform having a bail C. This bail projects loosely through guide-ears D, secured to the tub and has formed at the top an eye E.

Journalized in suitable hangers F is a shaft G, having thereon loose pulley H, which latter is constantly revolved by means of any suitable driving-belt. (Not shown.) At one end of this shaft is secured a crank I, having projecting laterally at its outer end a pin J, around which latter is swiveled an eye K, secured on the end of a rope U, the other end thereof being attached within the eye E of the bail C, so that it will be readily understood that at each revolution of the crank 65 the platform B will have been lowered and raised, for the purpose presently explained.

It is essential that the platform should remain in elevated position after dipping until 70 the substitution of a subsequent cone, and therefore I have illustrated various clutch devices and tripping mechanisms whereby the movement of the shaft G is controlled to effect the proper movements of said platform 75 at the proper time.

In Fig. 1, L is a collar rigid on the shaft G, and having extending laterally therethrough the clutch-pin M, adapted to slide freely in its bearings within said collar. A spring N, secured to the collar and bearing directly against the pin, serves to throw the latter forward. O is a trip attached to one of the hangers F so as to have a free vertical movement, and having an inclined heel P extending 80 therefrom across the face of the collar L and within the field of travel of the head Q of said pin. R is a lever pivoted to this hanger F, the upper end of said lever having an L shape, which latter engages a pin S, projecting 85 from the upper end of the trip O. In normal position the head Q of the pin is held retracted against the resiliency of the spring 90 95

N by means of the heel P of the trip, and when it is desired to dip the cone the lever R is pushed in the direction indicated by the arrow, thus elevating the trip and permitting 5 the spring N to throw the pin M within one of the several recesses T in the hub of the wheel H, thereby imparting motion to the shaft G. When the collar L has nearly completed a revolution, the head Q will strike 10 against the inclined heel P and thereby be forced back to normal position, thus withdrawing the pin M from engagement with the wheel H.

The above-described clutch and tripping 15 mechanism is well known and is in common use in various classes of machinery.

In Fig. 2 the bail of the platform B is suspended by a rope U, coiled around a pulley V on the shaft G, and power is communicated 20 from the pulley H to the shaft G by means of crown-clutches W, secured one to the hub of the pulley H and the other to a collar X, splined on the shaft G and actuated by the ordinary lever R. On the shaft G is secured 25 a drum Y, around which is wound a rope Z, to the end of which is attached a weight A', which is heavier than the weight suspended by the rope U. B is a cord secured at the lower end to the bail C, and at the upper end 30 run through an eye C', extending from the hanger F, and attached to the lever R. The position of the various parts being as is shown in Fig. 2, the revolution of the pulley H in the direction indicated by the arrow will uncoil the rope U from the pulley 35 V, and simultaneously wind the rope Z on the drum Y, thus lowering the platform B and dipping the cone, and also elevating the weight A'. The cord B' is of such length 40 that when the platform has been sufficiently lowered a side draft will be exerted on the lever R to disengage the clutches W, whereupon the weight A' will descend by gravity and elevate the platform to normal position 45 until the movement of the latter is arrested by the ears D.

In Fig. 3 I have shown two pulleys H revolving loosely on the shaft G in opposite directions, and the collar X is provided with 50 clutches on both sides, adapted by the movement of the lever R to be engaged alternately with clutches on the adjacent hubs of said pulleys. In this construction the weight A' is merely an equipoise, the dipping of the cone 55 being effected by means of the pulleys H. Pivoted to the lower end of the hanger F is a lever D', which is forked throughout the free end, as shown at G', so as to embrace the rod R and the rope U. E' is a button secured to 60 the rope U and adapted to elevate the lever D', for the purpose presently explained. When the collar X is engaged with the pulley shown at the left in Fig. 3, the motion imparted to the shaft G will cause the rope 65 U to be uncoiled from the pulley V, and the platform B will thus be lowered until the cord B' pulls the lever R and throws the col-

lar X into engagement with the other pulley, which revolves in a direction reverse to that of the previously-described pulley. The rope 70 U will now be coiled on the pulley V, and the platform will be elevated until the button E' has carried the lever D' so that the crotch in the fork of said lever will have abutted against the lever R and forced the same to 75 one side, thereby disengaging the clutch from the power-pulley and causing the platform to remain suspended by the weight A'.

In Fig. 4 I have shown an apparatus for dipping the hat-body controlled by hydraulic 80 pressure, and this construction is especially intended for use in factories where there is no steam-power convenient at hand for application as a motor. This apparatus consists of a cylinder H', within which runs an ordinary piston I', the rope which suspends the platform B running over suitable pulleys J', suspended from the ceiling, and thence through a pulley K', journaled at the top of the piston-rod without the cylinder, the end of 85 the rope being returned upward and secured to the top of a frame L', extending upward from said cylinder. To the rope is secured the weight A', which, together with the piston I', overbalances the weight of the platform 90 and the cone carried thereby, for the purpose presently explained. N' is a hand-lever pivoted at a to the frame L', and O' is a crank extending from a two-way cock P', seated within the supply-pipe Q'. A pitman R' connects the lever N' with the crank O', and a duct leads from the pipe Q' within the cylinder at the bottom thereof. The construction 95 of this two-way cock with relation to the cylinder and the pipe Q' is such that the operation 100 of the handle N' alternately admits a supply of water within the cylinder through the pipe Q' and then cuts off said supply, permitting the water in the cylinder to flow through the outlet-pipe T'. The lever N' has at its heel end 105 a projection U', and secured to the piston-rod is a trip V', which, when the piston is elevated, will engage this heel end U', and thereby force the crank O' downward to shut off the supply of water to the cylinder and 110 establish the communication between the latter and the outlet-pipe, as previously set forth. 115 W' is the relief-exit for the air at the top of the cylinder. The operation of the construction 120 just described is obviously as follows: After the cone has been placed on the platform, the operator pulls up the hand-lever N' to the position shown in the drawings, and water being thus led through the two-way cock P' within the cylinder the piston will 125 be raised by the water-pressure and the platform B will descend within the tub. During the raising of the piston the trip V' will engage with the projection U', which occurs just before the cone is completely submerged, 130 and the lever N' will thus be operated by the continued elevation of the piston to shut off the supply of water to the cylinder, and at the same time to establish communication

between the latter and the outlet-pipe T'. As the water runs out of the cylinder, the piston will sink, and its weight, together with that of the weight A', will raise the platform and cone out of the tub to normal position.

The construction shown at Figs. 5 and 7 is also intended for use in instances when it is not convenient to use steam or other motive power. The apparatus therein shown is very similar to that illustrated at Fig. 1, the platform being suspended and operated from the crank I on the shaft G. The pulley H is loose on this shaft and has sprocket-teeth X' projecting circumferentially therefrom. A spring-actuated pawl b, secured laterally to said pulley, engages with a ratchet Y', secured to the shaft G to establish a rigid connection between said shaft and pulley when the latter is revolved in the direction reverse to that indicated by the arrow. A sprocket-chain Z' is run over the pulley H, one end of the chain being connected to a treadle M' through the medium of the rope C, the other end having suspended therefrom the weight A', which latter overbalances the weight of the platform B and the cone carried thereby.

The operation of this apparatus is as follows: After placing the cone upon the platform the operator depresses the treadle M' to an extent sufficient to turn the pulley H loosely on the shaft G in the direction indicated by the arrow throughout one complete revolution, thus elevating the weight A'. To prevent the shaft G from revolving by friction with the pulley H when the latter is thus turned, a pawl d is pivoted to the hanger F' and engages with a ratchet e, rigid on the shaft G, to oppose any movement of said shaft in the direction indicated by the arrow in Fig. 7. The weight, being elevated as above set forth, will, when the treadle is released, descend by gravity, and, by revolving the pulley and shaft in the direction reverse to that indicated by the arrow, will dip and elevate the platform from without the tub to normal position.

In connection with any of these constructions hereinbefore set forth, a hat-forming machine requires the services of but one operator, since, when a hat is formed, he merely removes the cone with the hat thereon, places it on the platform B, which is convenient of access, trips the mechanism which effects the dipping, substitutes another cone in the forming-machine, superintends the initial formation of the hat-body, removes a preceding hat-body from the cone which in the meantime has been dipped, folds said body, deposits it on the table, removes the dipped cone from the platform, and has said cone in

position to substitute for the cone now in the forming-machine before the latter has finally completed the formation of the succeeding hat-body.

I have shown in the drawings various constructions by means of which the hat-body may be dipped automatically, and many other constructions would naturally suggest themselves to any ordinary mechanic who understood my invention; therefore I do not wish to be limited to the use of any particular mechanism for dipping the hat-body and then holding the same in suspense, the gist of my invention in this respect resting in the broad idea of dipping the hat-body automatically.

I claim—

1. In a machine for automatically dipping hat-bodies, the combination, with the cone-supporting platform, of a motor and a flexible connection extending between said platform and motor, substantially as set forth.

2. In an apparatus of the character described, a platform suspended over the tub by means of a rope or cable, the latter being attached to mechanism for vertically reciprocating said rope, substantially as and for the purposes set forth.

3. In a machine for automatically dipping hats, a mechanism for lowering and elevating a cone-supporting platform, said platform having connected thereto a counterbalancing-weight, substantially as set forth.

4. In a machine for dipping hats, a mechanism for lowering and elevating the hat-cone-supporting platform, comprising a rotary wheel, a clutch adapted to be operated thereby to dip the hat, and a counterbalancing-weight to elevate the same, substantially as set forth.

5. In a machine for dipping hats, a hat-cone-supporting platform connected to a dipping and elevating mechanism, comprising a power-driven lowering device and a connecting-weight for elevating the same, substantially as set forth.

6. A mechanism for dipping hats, comprising a platform, a driving mechanism for lowering the same, a counter-weight for elevating the same, said lowering apparatus being adapted to be automatically released at the desired point and the elevating-weight brought into action thereby, substantially as set forth.

In testimony whereof I affix my signature in presence of two witnesses.

SEYMOUR C. PALMER.
